UNITED STATES PATENT OFFICE.

WILLIAM C. BUCKELEW, OF SHREVEPORT, LOUISIANA, ASSIGNOR OF ONE-HALF TO CHARLES L. REIERNON, OF SHREVEPORT, LOUISIANA.

TRUCK.

SPECIFICATION forming part of Letters Patent No. 764,344, dated July 5, 1904.

Application filed October 29, 1903. Serial No. 179,092. (No model.)

To all whom it may concern:

Be it known that I, WILLIAM C. BUCKELEW, a citizen of the United States, residing at Shreveport, in the parish of Caddo and State of Louisiana, have invented new and useful Improvements in Trucks, of which the following is a specification.

This invention relates to trucks; and the object of the invention is to provide a simple yet stable device of this character which can be effectively used for a variety of purposes, such as the transportation of leather, rubber, or canvas belts and similarly rolled objects, kegs of nails, pipe, &c. The truck involves in its organization a pair of lifting devices for an article, separated at their working ends for the reception of such article therebetween. In the present instance these lifting devices consist of levers suitably connected for movement in unison and mounted upon a portable frame. Preferably the frame has an opening which coincides with the space between said levers in order that an object—such as a roll of leather, paper, or the like—can be introduced into said opening to bring a projecting shaft or mandrel of the roll under the working ends of the two levers. When the roll is in the position indicated, the levers may be manipulated, so as to raise the roll from a floor or other foundation upon which the truck travels, whereby the truck as a whole can be moved, means being provided to lock the levers in a position to hold the roll elevated, so as to facilitate the unwinding of the same.

I have set forth one highly advantageous adaptation of the device in one organization thereof. The lifting devices may be dismounted, and a platform or deck can be applied to the portable frame, so that the truck can be utilized for carrying nail-kegs, pipe, and other articles. The platform or deck when the truck is arranged for the handling of roll, is not in use, and ordinarily it will consist of a plurality of sections removably supported by the truck-frame.

The invention in one simple embodiment thereof is illustrated in the accompanying drawings, forming a part of this specification, and in which—

50 Figure 1 is a perspective view of a truck

involving my invention, showing the same arranged for handling rolls of leather or similar objects, the lifting devices constituting a part of the same being shown in the position they occupy prior to lifting such roll. Fig. 55 2 is a side elevation of the same, showing the truck locked against endwise movement during the unreeling of the roll. Fig. 3 is a perspective view with the roll-lifting devices dismounted. Fig. 4 is a detail view in top 60 plan of the roll-lifting member of the truck. Fig. 5 is a similar view of one of the sections of the removable deck or platform of said truck. Fig. 6 is a like view of a hollow core and shaft associated therewith. 65

Like characters refer to like parts throughout the several figures.

I desire to state at this point that I do not limit myself to the exact disclosure made by said drawings and the following description, 70 for certain variations as to several features of the invention may be made within the scope of the claim, succeeding said description.

The truck involves in its construction a frame of some suitable kind upon which the 75 different parts thereof are mounted. The frame illustrated embodies side sills or beams 2, arranged in parallelism, and cross pieces or ties 3, uniting the sills at suitable intervals along their length. The frame in order 80 to secure portability is mounted upon universally-movable rollers or wheels 4, four of said rollers or wheels being illustrated as located at the corners of the frame.

When the truck is arranged for handling 85 rolls and similar objects, what might be considered the forward end of the frame of the truck is open, thereby to permit the introduction of such article into the opening, which, as is obvious, is situated between the side sills or beams 2. When the said roll or other object is in the opening, a mechanical lifting member can be brought into use to elevate the roll into position to permit the unwinding or unreeling of the same, and incidentally its 90 transportation, by virtue of which no unnecessary manual labor is necessary to handle the heavy article.

The truck is portable, and in the construction thereof illustrated the roll of leather or 100

other material is adapted to be unwound toward the rear end of the truck-frame, and as considerable stress is applied to the frame during such an operation I provide positive 5 means to prevent endwise movement of the frame in the direction of the unwinding strip or band, and the means illustrated for this purpose will now be described. Each side sill carries a detent means for assuring the function just set forth, and as the detent means is the same in each case I will describe but one of them in detail.

Referring to Fig. 2, the numeral 5 denotes a detent or dog consisting of an elongated 15 arm pivotally mounted at one end to a sill 2, the free end of the detent or dog being sharpened or pointed to penetrate for a short distance a floor or like foundation. During the movement of the truck from place to place 20 the detent or dog 5 is not in operation, and at such time I provide means to hold it in its ineffective position. The means illustrated for this purpose is a latch 6, pivotally mounted upon the sill in proximity to the dog, the 25 latch having a shoulder at its free end to engage under the dog or detent 5 between its fulcrum and point to hold the dog in its inoperative position. The latch 6 is held in its working position by a spring 7. By pressing 30 the upper arm or finger-piece of the latch 6 inward the shoulder on the lower arm thereof will be moved out of engagement with the dog 5, so that the latter can drop. It will therefore be understood that the two dogs or 35 detents 5 are of the gravity type. Ordinarily both of them will be employed, although in some cases one of them will be sufficient to hold the truck-frame or carriage against movement during the unwinding of a strip of leather 40 or paper.

The lifting member for the roll or similar object when the truck is arranged for handling rolls or the like is shown as consisting of two devices, such as levers 8, mounted upon 45 uprights or standards 9 near what is considered the forward end of the truck. In the present case these levers are mounted for movement in unison, they being shown as connected for this purpose by a tie-bolt 10 between their fulcrums and handles. The connected levers 8 constitute, in effect, a duplex or compound lever, and they are separately and adjustably pivoted, by virtue of which latter fact the leverage thereof can be regulated to meet different conditions. Each upright or standard 9 consists of a pair of parallel vertically-disposed strips suitably fastened by bolts to the sills 2 and the respective strips being separated to receive between them 50 the coöoperating levers. Each lever has on the under side thereof a series of bearings or brackets 11 of approximately channel form to removably receive the pivots thereof, the bearings or brackets being arranged in a row, so 55 as to secure adjustment in leverage of the le-

vers. The pivots for the levers also removably pass through a series of vertically-arranged partitions 12, whereby the vertical position of the fulcrum thereof can be raised or lowered to adapt the lifting mechanism for 70 the handling of rolls or similar objects of different sizes. The uprights or standards 9 are held securely in place by the braces 13, extending diagonally downward and rearward from the upper ends thereof and fastened to 75 the sills 2.

The forward arms of the two levers constitute the carrying or object supporting portion thereof, and to prevent unnecessary wear on the effective surfaces thereof such surfaces are 80 provided with wear-plates 14, terminating at their forward ends in offsets 15. The plates may be secured to the levers in any desirable manner.

I have shown a band or strip of leather arranged in roll form at 16. (See Fig. 2.) Through the center of the roll 16 I pass the hollow core or sleeve 17, having nuts at its opposite ends to engage the side faces of the roll and to prevent lateral motion thereof on 90 the core and at the same time to provide for receiving rolls of different width on the core.

Prior to mounting the object upon the truck for its transportation and unwinding I insert 95 through the hollow core or sleeve 17 a shaft 18. The manner of mounting the roll upon the truck is as follows.

The truck is initially brought to the vicinity of the roll, and the core 17 is passed through the center thereof and fastened securely in 100 place by the manipulation of the nuts thereof, after which the shaft 18 is introduced, with the opposite ends of the shaft projecting substantially equidistantly from the sides of the roll. The rear ends of the two levers 8 are then 105 grasped in order to lower the forward or working ends thereof. The roll, with the parts applied thereto, is then moved into the space or opening between the forward ends of the sills 2. The forward ends of the levers will then be under the projecting ends of the shaft 18. The rear ends of the levers are then lowered, so as to elevate the working ends thereof, the result being that the roll is lifted, the offsets 15 at the extreme forward ends of said levers preventing 110 the roll from falling off the levers. As the rear ends of the levers are being moved toward their initial position the forward ends thereof will assume a downward inclination toward the rear of the truck, whereby the shaft 115 18 will roll along the wear-plates 14 until it encounters the standards or uprights 9, at which time further rearward motion of the roll is prevented, it being then in its elevated position and in condition to be unwound. 120 The roll can be unwound by simply engaging by hand the free end of the band thereof and unreeling the band, or a hand-crank (not shown) can be applied to the squared outer end of the shaft to turn the same. When the 125 130

- latter operation is performed, a pin or key 19 on the shaft will engage in a notch or key-way in the adjacent outer end of the tubular core 17.
- 5 During the unreeling operation it is desirable to provide means to hold the working ends of the levers 8 in their elevated position, and for this purpose I pivotally mount a latch 20 upon the tie-bolt 10, uniting the levers, said latch being of the gravity type and its operating end being adapted to engage automatically under a keeper 21 on one of the cross-pieces of the truck-frame just before the levers reach their extreme retracted positions. To bring the levers into position to elevate a roll, the latch 20 is disengaged from its keeper 21 by hand.
- I have described in detail the frame organized for handling rolls and analogous articles. The truck may be used with equal advantage for other and dissimilar purposes. Some of these are for transporting kegs of nails or pipe. In the latter uses the two levers 8 are preferably removed, and to support the said kegs or pipe the truck-frame is provided with a deck. This deck consists of a plurality of horizontally-aligned sections 22, having angular plates secured to their opposite ends, the horizontal portions of which are adapted to rest upon the tops of the two sills when the truck is to be used for carrying kegs.
- When the truck is to be used to lift objects or as a jack, the deck or platform sections 22 will of course be lifted from place, so that a roll can be moved into the opening between the sills 2 at their forward end, and the levers 8 will at the same time be mounted. These operations are ones that require the outlay of but very little time and no unusual labor.
- The rear ends of the sills or beams 2 are beveled, as at 23, and the handles of the two levers when the same are in their roll-supporting position fit closely against these beveled faces.
- Having thus described my invention, what I claim as new, and desire to secure by Letters Patent, is—
1. A portable truck combined with a pair of separated levers fulcrumed between their ends above the body of the truck and each lever having a handle, a rigid connection uniting the levers between their fulcrums and handles, and means associated with said rigid connection for holding the levers in a shifted position.
  2. A portable truck including a pair of parallel side sills each having a standard, a lever fulcrumed between its ends upon each standard, each lever having a handle at its rear end, a cross-bar uniting the levers between their fulcrums and handles, a latch movably sup-
- ported by the cross-bar, and a beam connecting said sills and provided with a keeper for engagement by the latch. 65
3. A truck and a pair of connected weight-lifting levers vertically and longitudinally adjustably supported on the truck.
4. A portable truck including a pair of parallel side sills each having an upright standard comprising vertical strips having alined perforations, levers between the strips, a pivot for each lever extending through alined perforations in the respective strips, and a rigid connection between the levers. 70
5. A portable truck provided with a pair of lifting-levers separated at their working ends for the reception of an article therebetween, and means for changing the fulcrums of the levers to thereby adjust the leverage thereof. 75
6. A portable truck including a pair of pivotally-mounted levers separated at their working ends for the reception of an article therebetween, each lever having a series of pivot-bearings extending longitudinally thereof, whereby the fulcrums of the levers can be changed. 80
7. A portable truck including a pair of parallel side sills, each having a standard, and a pair of parallel levers pivotally supported by the respective standards, each lever having a plurality of longitudinal brackets to interchangeably receive the respective pivots. 85
8. A portable truck including a pair of parallel side sills, each having a pointed detent, and a spring-actuated latch to hold the detent in an ineffective position, and standards upon the side sills, rising therefrom, each comprising vertical strips, braces between the standards and the sills, a pair of levers having adjustable fulcrums supported between said strips, and a rigid connection between the said levers. 90
9. A portable truck including a pair of parallel side sills, each provided with a standard comprising parallel strips, rigidly-connected levers pivotally supported between the respective strips, plates carried upon the forward arms of the levers, having upturned ends, braces between the standards and side sills, a cross-beam rigidly uniting said sills, a rod connecting the levers, and a latch pivotally supported by the rod, the cross-beam having a keeper for engagement by the latch 100 to hold the levers in shifted position. 100
- In testimony whereof I have hereunto set my hand in presence of two subscribing witnesses.
